UNITED STATES PATENT OFFICE

107,723

DESIGN FOR A DUPLEX HOUSE-COAT

Henry Leone, New Dorp, N. Y.

Application September 13, 1937, Serial No. 71,586

Term of patent 7 years

To all whom it may concern:

Be it known that I, Henry Leone, a citizen of the United States, residing at New Dorp, in the county of Richmond and State of New York, have invented a new, original, and ornamental design for a Duplex House-Coat, of which the following is a specification, reference being made to the accompanying drawing, forming part thereof.

Fig. 1 is a front view of a duplex house-coat showing my design, the front flaps being in open position.

Fig. 2 is a rear view of the duplex house-coat shown in Fig. 1; and

Fig. 3 is a front view similar to Fig. 1 showing the front flaps in closed position.

The panel-like element extending to about the full length of the garment between the rever flaps, is an integral part of the house-coat and comprises an upper front blouse-like section terminating into a lower divided skirt and leg sections, as shown.

I claim:

The ornamental design for a duplex house-coat, as shown and described.

HENRY LEONE.
